UNITED STATES PATENT OFFICE

GEORGE BODEN, OF WATERBURY, CONNECTICUT, ASSIGNOR TO SCOVILL MANUFACTURING COMPANY, OF WATERBURY, CONNECTICUT, A CORPORATION OF CONNECTICUT

PINHOLDER

Application filed April 9, 1929. Serial No. 353,858.

This invention relates to certain improvements in pin cases of that class in which the pins are mechanically delivered from the case.

5 A pin case of this character is shown in United States Letters Patent No. 1,586,359, dated May 25, 1926, to J. F. Franzen, and the invention has for its especial objects improvements in the construction of the pin case of the type shown in the Franzen patent in the following particulars, to wit: the provision of means for preventing the pins from upsetting or improperly intermingling in the event that the pin case or holder is 10 overturned, or for other reasons; the provision of means for preventing the pins jamming during the dispensing operation; the provision of means for preventing the delivery of more than one pin at a time; and the provision of a removable cover with 15 means for holding the cover in place during the dispensing operation.

With these and other objects not specifically referred to in view, the invention consists in certain novel parts, arrangements and combinations which will be described in connection with the accompanying drawings and the novel features pointed out in the claims hereunto annexed.

30 In these drawings,—

Figure 1 is a perspective view of the pin case embodying features of the invention;

Figure 2 is a central vertical section of the holder shown in Figure 1;

35 Figure 3 is a view similar to Figure 2 showing the parts in another position;

Figure 4 is a similar view showing the parts in the position assumed when ejecting a pin;

40 Figure 5 is a top view of the holder shown in Figure 1 with the cover removed;

Figure 6 is a bottom view of the cover, and

Figure 7 is a detail sectional view taken on line 7—7 of Figure 6.

45 Referring now to these drawings, the pin

construction of the holder will be substantially like that of the Franzen patent above referred to, including a casing 1 having an enlarged base 2 so that the case will remain upright on a desk or the like, this casing being made of any material, as for instance a suitable plastic composition which can be readily moulded. Cooperating with this casing is a pin carrier, which may be of similar composition material, marked 3, this carrier having an interior recess 4 provided with bottom walls 5, 6, which slope toward each other, this recess or compartment 4 acting to hold the pins, one of which is shown marked 7, the pins being arranged in the carrier with the points in one direction, that is, pointing downwardly.

50 This carrier is provided with an aperture 8 extending through the bottom wall thereof, through which is arranged to extend a pin dispenser in the form of a rod 9 stationarily mounted in the casing, the end of this rod being notched, as at 10, so as to grasp the head of a pin, as clearly shown in Figures 3 and 4. This pin carrier is arranged to 55 have a sliding movement relatively to the casing 1, this movement being against a spring 11. It will be observed that by moving the carrier down the pin dispenser extends through the aperture in the casing, 60 seizes a pin and lifts the pin to dispensing 65 position.

70 In accordance with one feature of the invention means are provided whereby entrance of the pins into the aperture 8 is prevented, this avoiding jamming of the pins 75 at this point. In the particular construction shown for this there is located at a suitable point in the aperture, preferably adjacent its mouth, a guide shown in the form of a metal plate 12 having a curved guiding surface 13, as shown in Figure 5, through which 80 the pin dispenser works, this guide acting as a bearing for the dispenser and at the same time preventing pins from entering the aper- 85

ture and jamming the parts when the pin carrier is given its downward movement.

Cooperating with the carrier is a cover and certain attachments therefor, which 5 form important features of the invention. As illustrated, this cover includes a plate 14, which may be of composition material, which plate is removably associated with the top of the pin carrier.

10 This cover plate is provided with a dispensing orifice, and in accordance with one feature of the invention this dispensing orifice is so arranged as to prevent more than one pin being dispensed at a time. 15 While the means for effecting this may be somewhat varied, in the particular construction illustrated the dispensing orifice is in the form of an eyelet 15, and secured in place by this eyelet is a bar or strip of metal 16, which extends across the cover, the strip being held at one end by the eyelet and at the other end being turned up to form a catch member 17, which cooperates with a spring strip 18 secured in place on the inside 20 of the pin carrier by an eyelet 19, this acting to lock the cover in place. This metal strip, at each side of the eyelet, is formed with short depending guides, best shown in Figure 6, marked 20, these guides being 25 shown in the form of wings which act to strip off a pin if more than one pin should happen to be seized by the pin dispenser. It will be observed that this dispensing eyelet is opposite the aperture 8, before referred to, 30 and the provision of the guide 13 and the stripper or guide wings 20 insure the proper delivery of a single pin through the dispensing orifice.

35 In accordance with a further feature of the invention means are provided for preventing the upsetting or mixing up of the pins in the event that the pin case is accidentally tipped over or for any other reason. While these means may be of various character, in the particular construction 40 illustrated such means are in the form of a baffle plate of thin metal, marked 21, this being shown in the form of a tongue which extends downwardly into the pin carrier. 45 While this baffle may be supported in any suitable way, a convenient one is that shown in which the baffle is formed integrally with the bar or strip 16, before referred to. The provision of this baffle extending down into 50 the carrier acts as a guard for preventing the pins from upsetting or becoming mixed up, this being particularly effective where a large number of pins are used in the carrier.

55 Where a removable cover is employed secured by a spring catch, it is desirable that some means be provided for preventing the cover from being accidentally displaced from the case, but at the same time permitting 60 its ready removal for the purpose of re-

loading the pin carrier. While such means may vary widely, a convenient one is that shown in which the end of the bar adjacent the eyelet is bent downwardly and slightly outwardly, as indicated at 22, this affording 70 a resilient friction hold against the inner wall of the carrier, so that the cover is held in position against accidental displacement.

75 While the invention has been shown and described as to its various features in their preferred forms, it will be understood that certain modifications in the form and arrangement of the parts constituting these features is permissible without departing from the spirit and scope of the invention as defined in the appended claims.

80 What I claim is:

1. In a pin case from which the pins are delivered mechanically, the combination of a 85 casing, a pin carrier slidable relatively to the casing and having an aperture, a pin dispenser in the casing extending into the aperture, and a curved rigid guide and stop through which the dispenser passes so located as to prevent pins passing into the aperture. 90

2. In a pin case from which the pins are delivered mechanically, the combination of a 95 casing, a pin carrier slidable relatively to the casing and having an aperture, a pin dispenser in the casing extending into the aperture, a rigid guide through which the dispenser passes located to prevent pins passing into the aperture, a cover over the carrier, a dispensing eyelet in the cover in line with the aperture, and guides around the eyelet to prevent the delivery of more than one pin at an operation of the dispenser. 100

3. In a pin case from which the pins are delivered mechanically, the combination of a 105 casing, a pin carrier slidable relatively to the casing, a pin dispenser in the casing extending into the carrier, a cover for the carrier, and a baffle plate in the carrier extending down into the pins in the casing and acting to prevent the pins in the carrier from upsetting. 110

4. In a pin case from which the pins are delivered mechanically, the combination of a 115 casing, a pin carrier slidable relatively to the casing, a pin dispenser in the casing extending into the carrier, a cover for the carrier, and a baffle plate depending from the cover into the carrier extending down into the pins in the casing and acting to prevent the pins in the carrier from upsetting. 120

5. In a pin case from which the pins are delivered mechanically, the combination of a 125 casing, a pin carrier slidable relatively to the casing, a pin dispenser in the casing extending into the carrier, a cover for the carrier, an eyelet in the cover, a bar extending across the under side of the cover and held in position by the eyelet, and a baffle plate integral with the bar and extending into the carrier.

6. In a pin case from which the pins are

delivered mechanically, the combination of a casing, a pin carrier slideable relatively to the casing, a pin dispenser in the casing extending into the carrier, a cover for the carrier, an eyelet in the cover, a bar extending across the under side of the cover and held in position by the eyelet, a baffle plate integral with the bar and extending into the carrier, and a spring catch cooperating with one end of the bar for removably holding the cover in place.

10 In testimony whereof, I have hereunto set my hand.

GEORGE BODEN.
